UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

SPLITTING AND BUFFING MACHINE.

1,395,268.

Specification of Letters Patent.

Patented Nov. 1, 1921.

Application filed January 2, 1920. Serial No. 348,861.

To all whom it may concern:

Be it known that I, FREDERICK M. FURBER, a citizen of the United States, residing at Revere, in the county of Suffolk and State 5 of Massachusetts, have invented certain Improvements in Splitting and Buffing Machines, of which the following description, in connection with the accompanying drawings, is a specification, like reference characters on the drawings indicating like parts in the several figures.

This invention relates to machines for use in the manufacture of boots and shoes and is herein illustrated as embodied in a machine for forming a flap on the rear end of a sole and for buffing one surface of the flap and part of the contiguous surface of the sole.

It is customary, when a shoe having a 20 wooden Louis heel is being made, to produce on the heel end of the unattached sole a thin flap which, after the sole has been attached, is bent down away from the sole and cemented to the breast of the heel to serve as

25 a covering for the breast thereof; and subsequently the bottom of the sole and the exposed surface of the flap, which then covers the breast of the heel, are buffed in preparation for the application of stain.

30 The forepart of the bottom of the shoe is buffed on the usual shoe bottom buffing machine; but, owing to the size of the rolls of that machine and to the peculiar curvature of the breast of a Louis heel, it is not possible to buff either the breast of the heel or 35 a considerable part of the shank portion of the sole. Consequently it has been customary to buff the breast of the heel and the contiguous portion of the surface of the 40 shank of the sole by hand.

According to one feature of the present invention, the forming of the flap as well as the buffing of the flap and the contiguous surface of the shank portion of the sole is 45 accomplished at a single operation so that no hand buffing of these parts is necessary after the heel has been attached. In the illustrative machine the sole is placed upon a support or bed over which a carrier is

caused to make one complete reciprocation 50 and then come to rest. Mounted on the carrier is a flap-forming mechanism and a buffing tool the latter being spaced from and in front of the former. On the forward stroke, while the flap-forming mechanism is 55 operating, the buffing tool is held in inoperative position. On the return stroke, the buffing tool is brought down upon the sole at a locality in proximity to the forward end of the shank portion of the sole and caused 60 to buff the bottom of the sole, including the exposed surface of the newly-formed flap, from that locality to the extreme heel end of the flap. The further steps in the manufacture of a shoe, using the sole thus treated, 65 are the same as have been carried out heretofore except that the buffing of the exposed surface of the flap after it has been cemented to the breast of the heel and of the contiguous surface of the shank portion of the sole 70 is no longer necessary since these surfaces have already been buffed.

This and other features of the invention, including certain details of construction and combinations of parts, will be described as 75 embodied in an illustrative machine and pointed out in the appended claims.

Referring now to the accompanying drawings,

Figure 1 is a side elevation of a machine 80 in which the present invention is embodied, and

Fig. 2 is a perspective of a sole after it has been operated upon by the machine.

The machine chosen for illustration is 85 similar in many respects to the machine of Patent No. 1,224,918 and before proceeding to the new features, those common to the two machines will be described briefly. The machine comprises a frame 3 upon which a bed 90 or work support 5 is indirectly mounted, such mounting comprising rollers 7 which are yieldingly maintained in the raised position shown by springs (not shown). These rollers extend through oblique slots 9 in 95 flanges which are fast to the bed, the bed itself being free to move to the right or left except as limited by the slots and flanges

and being capable of yielding downwardly with the rollers when force is applied to the surface of the support. Normally the support is as shown at the limit of its left-hand movement with the rollers at the right-hand or upper ends of the slots 9 but will be raised slightly by being moved to the right before the knife enters the sole 100. Slidable on the frame is a carrier 11 which is caused to make one reciprocation over the support and then come to rest by tripping a one-revolution clutch and thereby causing a segment 13 to make a complete revolution. This segment is pivoted to the rear end of a connecting rod 15 the forward end of which is indirectly connected by a pivot 17 to the carriage. This connection is not the same as in the patented machine, as will presently appear, but the general effect of the clutch, connecting-rod and connections in both cases is to cause the carrier 11 to make one complete reciprocation. Mounted rigidly in the carrier is a knife 19, and pivotally mounted in the carrier just in front of the knife is a gage or presser 21 upon the angular position of which depends the thickness of the flap produced by the knife. If the support 5 remained in the lowered position shown and the carrier 11 were reciprocated, it is clear from the drawing that the knife would either pass entirely over the sole 100 or at most would just graze it. In order to cause the knife to enter the sole and produce the desired flap, the support 5 is raised automatically after the carrier starts its forward movement. The support carries at its rear end a pin on which is mounted a roller 23 which lies in the path of a segmental plate 25, said plate being fast to the rotatable segment 13. The support has also at its rear end an eye 27 through which passes loosely a screw 29 carrying near its rear end a stop nut 31 and having its forward end threaded into the frame of the machine. A coiled spring 33 encircles the screw and normally maintains the support in its left-hand lowered position, as shown, with the rollers 7 in the right-hand ends of the slots 9. When, however, the segment 13 is rotated, the segmental plate rides upon the roller 23 thereby moving the support 5 to the right and causing it to rise by reason of the engagement of the slots 9 with the rollers 7. This raising of the support may be caused to occur either before or after the knife reaches the rear end of the sole according to the position to which the plate 25 is adjusted with respect to the segment 13. In order to cut a sole in the manner shown in Fig. 2, which is the usual manner, the support is raised before the knife reaches the locality of the sole. The gage 21 may be adjusted angularly to predetermine the thickness of the flap 200 which will be produced. In the operation of the machine a sole 100 is placed upon the

support 5 in the position shown and the clutch is tripped. The carrier with its knife 19 and gage 21 moves forward a short distance, but before the knife reaches the sole the segmental plate 25 rides upon the roller 23 thereby raising the support and holding it raised during the forward movement of the knife. Just as the knife starts its rearward or withdrawing movement, the segmental plate 25 runs off the roller 23, and the support moves downwardly and to the left into the position shown so as to prevent the gage from dragging over and stretching the flap 200 which has just been produced. The machine as thus far described, except for the connection of the connecting rod 15 with the carrier 11 and the fact that the gage is not automatically adjusted, is substantially like the patented machine, and no further detailed description of this part of the machine will be given.

The purpose of forming the flap 200 is to provide a covering for the breast of a Louis heel which will be attached to the sole in the manufacture of a shoe. It is desirable before the shoe is finished to buff the exposed face of this flap as well as the entire bottom of the sole. Hitherto the sole has been buffed by means of a machine having rolls which are two or three inches in diameter. With such rolls it is impossible to buff either the exposed face of the flap after it has been cemented to the breast of a Louis heel or to buff the contiguous surface of the shank of the sole. It is not economical to use a small buffering roll owing to the frequency with which the abrasive covers must be renewed nor is it feasible with a roll, however small, to buff the breasts of Louis heels since these breasts often curve in two directions. For all these reasons it has been customary to buff the breasts of such heels and the contiguous portions of the shanks of the soles by hand. According to the present invention the rear portion of the sole, including that portion of the shank which was formerly buffed by hand, is buffed in the same operation in which the flap is formed.

In the illustrative machine the flap-forming operation is completed before the buffering operation is begun, but it should be understood that in its broader aspects the invention is not limited to any particular sequence or timing of the two operations.

The buffering mechanism comprises a buffering roll 35 rotatably mounted in a yoke 37 which is pivoted on a rod 39 between upstanding ears 41 rigid with the carrier 11. This roll is driven continuously by a belt 125 43 which passes around a pulley on the roll shaft 45, over a pulley 47, around a driving pulley 49, and around a pulley 51. The pulley 49 is fast to the driving shaft 53 which is rotated continuously and from 130

which power is taken by throwing in the one-revolution clutch referred to above so as to cause reciprocation of the carrier 11 when desired. The pulley 51 is mounted on 5 a pin 55 carried by the stem of a double yoke 57 the arms of which are pivoted on the shaft 53. The pulley 47 is rotatably mounted in a block 59 which is slidable in a small yoke 61 formed at the upper end 10 of the stem of the large yoke 57 and is urged upwardly at all times by a spring 63 the lower end of which is attached to the block 59 through a pin 65 and the upper end to a pin 67, the latter pin being 15 fast to a bar 69 which is rigid with the small yoke 61. Pivoted to one arm of the yoke 61 at 71 is the stem of a yoke 73, the arms of which are pivoted on the rod 39. The construction which has just been 20 described provides means for maintaining the belt 43 taut during the reciprocation of the carrier 11 and for rotating the roll 35 continuously.

In the illustrative machine the roll is 25 raised and held in raised inoperative position during the forward movement of the roll and carrier and is brought down upon the sole during the return movement. To this end two lost motion connections are 30 provided. The pivot 17 upon which the forward end of the connecting rod 15 is mounted is carried by a slide 75 which is slidably mounted in suitable ways formed in the carrier 11, said block having formed 35 on its under side two lugs 77 between which extends a pin 79 which is held rigidly by its ends in the carrier. Consequently, after the machine has come to rest with the parts in the position shown and power is applied 40 to the machine to cause the connection rod 15 to start its forward movement, the slide 75 moves forward without moving the carrier until the rear lug 77 contacts with the pin 79 after which the carrier moves. Again, 45 when the forward half of the reciprocation of the carrier has been completed and the connecting rod 15 starts its backward movement, the slide 75 is pulled backward until the forward lug 77 contacts with the pin 79 50 before the carrier begins its backward movement. This mode of operation may not always occur just as described because a stop-screw 87 may be used but for the present it will be assumed that the stop screw 55 is not present. There are thus two occurrences of lost motion between the slide 75 and the carrier during each complete reciprocation of the carrier; and these two occurrences are utilized to raise and lower 60 the roll 35 at the proper times. To accomplish this raising and lowering, the slide 75 is forked at its forward end and carries a pin 81 upon which is swiveled a block 83, said block being located between two lugs 65 85, which are integral with the hub of the 70 yoke 37. The extent of the lost motion permitted between the block 83 and the lugs 85 is considerably less than that permitted between the lugs 77 and the pin 79 so that the roll 35 will be raised before the carrier 75 starts its forward movement and will be brought down upon the sole before the carrier starts its rearward movement. An adjustable stop screw 87 may be provided if 80 desired for limiting the downward movement of the roll toward the work support. This stop screw may contact with the carrier 85 at the same time that the forward lug 77 contacts with the pin 79 in which case the lug and the screw may both function in the backward movement of the carrier. If, however, the screw is so adjusted, as shown, that it contacts with the carrier before the forward lug 77 in its backward movement contacts with the pin 79, then, of course, the contact of the screw with the carrier determines the time when the carrier starts its backward movement.

Assuming, in order to promote brevity of description, that the stop screw 87 is in a 90 position shown and that the machine is at rest, the operation is as follows: The operator places a sole 100 on the bed or support 5 in the position shown in Fig. 1 and trips the one-revolution clutch. As the connecting 95 rod 15 moves forward, the slide 75 is first moved by it, the carrier 11 remaining stationary owing to its weight and the friction of its sliding contact with the frame of the machine. Presently the block 83 strikes the 100 forward lug 85 and raises the roll 35, then the rear lug 77 strikes the rod 79 and starts the forward movement of the carrier. Before the knife reaches the end of the sole toward which it is traveling, the segmental 105 plate 25 rides upon the roll 23 thereby pushing the support 5 forward and causing it to rise and bring the sole into the proper level with respect to the knife and gage. As the carrier completes its forward stroke the heel 110 end of the sole is split to form a thin flap 200 as shown in Fig. 2. At about this time, the segmental plate 25 runs off the roll 23 and permits the spring 33 to move the support 5 to the left and thereby lower the support and the sole slightly. As the connecting rod moves back (to the left) the slide 75 is moved before the carrier is moved. The first effect is to cause the block 83 to contact 115 with the rear lug 85 and bring the roll 35 down upon the sole at a point which is indicated by the extent of the buffed surface shown in Fig. 2. The extent of the downward movement of the roll is limited by the contact of the lower end of the stop screw 87 with the carrier if the screw is set in the position shown. Thereafter the carrier 11 moves rearwardly (to the left) and finally comes to rest in the position shown. During 120 this rearward movement the roll runs on the 125 130

4
sole and buffs most of the shank portion of the sole and all of the exposed surface of the newly-formed flap. The invention has been set forth as embodied in a machine in which 5 a carrier supporting a knife and buffing roll is movable over a sole supporting bed; but it should be understood that this particular type of machine has been shown merely by way of illustration and that the invention in 10 its broader aspects is not limited to this or any other particular type of machine since applicant believes that he is the first to split and buff a piece of stock in one operation.

Having thus described my invention, what 15 I claim as new and desire to secure by Letters Patent of the United States is:

1. A machine of the class described, having in combination, means for forming a flap upon a piece of stock, and means for 20 removing material from the flap.

2. A machine of the class described, having in combination, means for forming a flap upon a piece of stock, and means for buffing 25 the flap.

25 3. A machine of the class described, having in combination, a cutting tool, a buffing tool, and means for causing the tools to operate upon a piece of stock to form thereon a flap one face of which is buffed.

30 4. A machine of the class described, having in combination, a cutting tool, a buffing tool, means for supporting a piece of stock, and means for causing relative movement between the supporting means and the tools, to 35 cause the tools to operate upon the stock.

5. A machine of the class described, having in combination, a cutting tool, a buffing tool, means for supporting a piece of stock, and means for causing relative movement 40 between the supporting means and the tools in such manner as to form upon the stock a flap one face of which is buffed.

6. A machine of the class described, having in combination, a support for a piece of 45 stock, a cutter, means for producing relative movement between the support and the cutter first in a direction to cause the cutter to enter the stock and form a flap thereon and then in a direction to cause the cutter to be 50 withdrawn from the stock, and means for buffing the stock.

7. A machine of the class described, having in combination, a support for a piece of stock, a cutter, means for producing relative 55 movement between the support and the cutter first in a direction to cause the cutter to enter the stock and form a flap thereon and then in a direction to cause the cutter to be withdrawn from the stock, and means operating 60 during the withdrawal for buffing the flap.

8. A machine of the class described, having in combination, means for forming a flap on the heel portion of a sole extending 65 from the extreme heel end to approximately

the rear part of the shank portion, and means for buffing the entire flap and part of the shank portion of the sole.

9. A machine of the class described, having in combination, means for supporting a 70 sole, a flap-cutting tool, a buffering tool spaced from the flap-cutting tool, and means for producing between the supported sole and the tools relative movement of sufficient extent to cause the buffering tool to operate upon 75 a greater extent of the sole than does the flap-cutting tool.

10. A machine of the class described, having in combination, a cutter, means for causing the cutter to form a flap upon a piece of 80 stock, a buffering tool, and means for causing the tool to buff the flap.

11. A machine of the class described, having in combination, a cutter, means for causing the cutter to form a flap upon a piece 85 of stock, a buffering tool, means for rotating the tool, and means for causing the tool to buff the flap.

12. A machine of the class described, having in combination, a support for a piece of 90 stock, a carrier, flap-forming and buffering mechanism mounted on the carrier, and means for producing relative movement between the support and the carrier to cause the mechanisms to operate upon the stock. 95

13. A machine of the class described, having in combination, a support for a piece of stock, a carrier, flap-forming and buffering mechanism mounted on the carrier, and means for producing relative movement between the support and the carrier first to cause the flap-forming mechanism and then the buffering mechanism to operate upon the stock. 100

14. A machine of the class described, having in combination, a cutter, means for causing the cutter to form a flap upon a piece of stock, a buffering tool, and means for holding the tool out of contact with the stock during the formation of the flap and for thereafter causing it to contact with and buff the flap. 105

15. A machine of the class described, having in combination, a support for a piece of stock, a carrier, means for causing relative 110 reciprocation between the support and carrier, a cutter rigidly fastened to the carrier, an abrading tool mounted on the carrier and movable with respect thereto into and out of operative position, and means for so moving 115 the tool during each reciprocation.

16. A machine of the class described, having in combination, a support for a piece of stock, a carrier, means for reciprocating the carrier over the support, a cutter rigidly 120 fastened to the carrier, an abrading tool mounted on the carrier and movable into and out of operative relation with respect to the support, and means for holding the tool out 125 of operative relation during part of the re- 130

ciprocation and for moving it into operative relation before the reciprocation is completed.

17. A machine of the class described, having in combination, a support for a piece of stock, a carrier mounted for reciprocation over the support, a cutter fast to the carrier, an arm pivoted to the carrier, a buffing roll

mounted on the arm, an actuator for the carrier having a lost motion connection therewith and lugs on the arm located in the path of the actuator. 10

In testimony whereof I have signed my name to this specification.

FREDERICK M. FURBER.
